MATTRESS

Joseph Martin, Laurelton, N. Y., assignor to
 United States Cabinet Bed Co., Brooklyn, N. Y.,
 a corporation of New York

Application February 5, 1944, Serial No. 521,192

3 Claims. (Cl. 5—359)

This invention relates to mattresses in general.

Among the objects of the present invention it is aimed to provide an improved mattress having a yieldable interior and quilted supporting surfaces.

These and other features, capabilities and advantages of the invention will appear from the subjoined detail description of one specific embodiment thereof illustrated in the accompanying drawing in which

Figure 1 is a plan view partly broken away.

Fig. 2 is a fragmental section on the line 2—2 of Fig. 1.

Fig. 3 is a fragmental section on the line 3—3 of Fig. 2.

Fig. 4 is a fragmental elevation of an end of the mattress.

The mattress consists essentially of an inner envelope 1 provided with a plurality of transversely extending textile partitions 2 to form a plurality of compartments 3, which compartments 3 in turn are provided to receive a plurality of yieldable fillers such as rolls of felt 4, and an outer envelope 5, the upper and lower layers 6 and 7, respectively of which form with the upper and lower layers 8 and 9 of the inner envelope 1 enclosures to receive comparatively thin fillers 10 and 11 of yieldable material composed of felt, cotton or the like. The outer envelope 5 also has side walls 12 composed of fabric or the like disposed adjacent to the side wall 13 of the inner envelope 1.

In the interest of producing a quilted effect for the supporting surfaces of the mattress, thereby obtaining the many advantages of a quilted structure, namely of retaining the filler against accidental displacement and maintaining it uniformly distributed throughout the supporting surface, the outer layer 6, filler 10 and inner layer 8 are provided with a plurality of longitudinally extending rows 14 of stitches, and a second plurality of rows 15 of transversely extending stitches, the transversely extending rows 15 in the present instance alining substantially with the partitions 2. The transversely extending rows 15 of stitches connect the walls of said inner and outer envelopes and the intervening fillers 10 and 11 to one another, thereby anchoring the outer envelope and the fillers firmly to the fabric covering of the envelope 1. Preferably, as shown, the transverse stitches are attached directly to the partitions 2, thereby forming definite depressions that cannot be displaced. The transversely extending rows 15 thus cooperate not

only with the partitions 2, but with the rows 14 of stitches and fillers 10 and 4 to provide a plurality of uniform quilted or cushioning bulges. These quilted or cushioning bulges cooperate 5 readily to conform to the body being supported and yet anchor the fillers 10 against displacement. Furthermore, it is thus possible to use an inner rugged ticking or fabric for the envelope 1 and an outer ornamental fabric of 10 finer material composed of silk, artificial silk in the form of satin or the like or fabrics composed of other well known fibres. The layers 7 and 9 and fillers 11 are secured to one another by similar transversely extending and longitudinally 15 extending rows of stitches. The walls 12 and 13, on the other hand, in the interest of strengthening these walls and also thereby securing the fillers 4 adjacent such walls from displacement are secured in place by stitches 16 spaced from 20 one another as more clearly shown in Fig. 4.

It is, of course, obvious that ordinarily the outer envelope 5 composed of the outer layers 6, 7 and walls 12 may all be composed of one and the same ornamental finer material, and 25 that the inner envelope 1 consisting of the inner layers 8, 9 and walls 13 would ordinarily be composed of the same rugged ticking or the like fabric.

Preferably as shown, the edges of the mattress 30 have a U shaped tape stitched in place to the edges of the layers 6, 8, 7, 9 and walls 12 and 13, where they meet, see for instance the stitches 17 for the tapes 18.

The mattress is here shown provided with ten 35 transversely extending pockets or compartments 3, but the number, of course, may vary without departing from the general spirit of the invention.

Preferably, the size of the pockets and size 40 of fillers also vary with the widest pockets at the middle, with the narrowest pockets at the ends of the mattress, and with the intermediately sized pockets between the end pockets and the middle pockets, substantially as shown in Patent 45 No. 2,332,957.

It is obvious that various changes and modifications may be made to the details of construction without departing from the general spirit of the invention as set forth in the appended 50 claims.

I claim:

1. In a mattress, the combination of an inner fabric envelope having an upper wall, a lower wall and side and end walls, transversely extending fabric partitions secured to the upper and

lower walls to form transversely extending pockets, rolls of yieldable fillers disposed in said pockets and extending transversely of the mattress, an outer fabric envelope having an upper wall, a lower wall and side and end walls, a flat comparatively thin filler of yieldable material disposed between the upper walls of said inner and outer envelopes, a second flat comparatively thin filler of yieldable material disposed between the lower walls of said inner and outer envelopes, transversely extending rows of stitches respectively in alinement with the edges of the respective partitions and connecting the upper walls of said inner and outer envelopes and intervening filler to one another and other transversely extending rows of stitches also respectively alined with the edges of the respective partitions connecting the lower walls of said inner and outer envelopes and intervening filler to one another, and longitudinally extending rows of stitches connecting the upper walls of said inner and outer envelopes and intervening filler to one another to form quilted bulges.

2. In a mattress, the combination of an inner fabric envelope having an upper wall, a lower wall and side and end walls, transversely extending fabric partitions secured to the upper and lower walls to form transversely extending pockets, rolls of yieldable fillers disposed in said pockets and extending transversely of the mattress, an outer fabric envelope having an upper wall, a lower wall and side and end walls, a flat comparatively thin filler of yieldable material disposed between the upper walls of said inner and outer envelopes, a second flat comparatively thin filler of yieldable material disposed between the lower walls of said inner and outer envelopes, transversely extending rows of stitches respectively in alinement with the edges of the partitions and connecting the upper walls of said inner and outer envelopes and intervening filler to one another and other transversely extending rows of stitches also respectively alined with

the edges of the respective partitions connecting the lower walls of said inner and outer envelopes and intervening filler to one another, longitudinally extending rows of stitches connecting the upper walls of said inner and outer envelopes and intervening filler to one another and other longitudinally extending rows of stitches connecting the lower walls of said inner and outer envelopes and intervening filler to one another to form quilted bulges, and spaced apart stitches connecting said side and end walls and the adjacent portions of said filler rolls to one another to form firm side and end walls for the mattress.

3. In a mattress, the combination of an inner envelope composed of a rugged ticking material having an upper wall, a lower wall and side and end walls, transversely extending fabric partitions secured to the upper and lower walls to form transversely extending pockets, rolls of felt disposed in said pockets and extending transversely of the mattress, an outer envelope composed of an ornamental fabric having an upper wall, a lower wall and side and end walls, a flat comparatively thin section of felt disposed between the upper walls of said inner and outer envelopes, a second flat comparatively thin section of felt disposed between the lower walls of said inner and outer envelopes, transversely extending rows of stitches respectively in alinement with the edges of the respective partitions and connecting the upper walls of said inner and outer envelopes and intervening section of felt to one another and other transversely extending rows of stitches also respectively alined with the edges of the respective partitions connecting the lower walls of said inner and outer envelopes and intervening section of felt to one another, and longitudinally extending rows of stitches connecting the upper walls of said inner and outer envelopes and intervening section of felt to one another and other longitudinally extending rows of stitches connecting the lower walls of said inner and outer envelopes and intervening section of felt to one another to form quilted bulges.

JOSEPH MARTIN.
